UNITED STATES PATENT OFFICE.

WILLIAM SWARBRICK, OF AINTREE, ENGLAND.

SPRING-ROLLER FOR WINDOW-BLINDS.

SPECIFICATION forming part of Letters Patent No. 625,366, dated May 23, 1899.

Application filed December 5, 1898, Serial No. 698,365. (No model.)

To all whom it may concern:

Be it known that I, WILLIAM SWARBRICK, a subject of the Queen of Great Britain, residing at 4 Matlock avenue, Aintree, near Liverpool, in the county of Lancaster, England, have invented certain new and useful Improvements in Spring-Rollers for Window-Blinds, of which the following is a specification.

10 My invention relates to spring-rollers for window-blinds of the kind which comprise a central spindle around which is coiled a spiral spring, said spindle being fixedly attached to the window-frame by means of 15 brackets at each end, and an external roller journaled at each end upon said spindle and free to revolve thereon. One end of the spiral spring is attached to the spindle and the other to the roller. The blind is rolled around the 20 roller, and when it is pulled down by hand it causes said roller to rotate upon the spindle, thus putting tension upon the spring. On the blind being released the expansion of the spring causes a rotation of the roller in 25 the opposite direction, and the blind is thus rerolled thereon. At one end of the spindle is arranged a concentric race or track having at its top a sunk notch, and adjacent to said race the roller carries one or more pawls, which 30 ride over it and are adapted to fall by gravity into engaging position with said notch, and thus to hold the roller when desired against the influence of the spiral spring. When the motion of the roller is quick, the pawls have 35 not time to drop into said notch, and therefore skip over it; but if the motion is slow or braked one of the pawls may be allowed to drop into the notch, and thus maintain the roller, and consequently the blind, in desired 40 position. It is usual to provide two notches in the race at opposite points, either of which may be placed uppermost and therefore operative according to chance when the spindle is primarily fixed in its supporting-brackets.

45 The devices and arrangements above described are common knowledge and of themselves form no part of my invention, which has for its object to improve their construction so as to produce a more convenient and 50 durable combination, all as hereinafter pointed out and claimed.

In the drawings, Figure 1 is a sectional ele-

vation of such portions of a spring-roller as are necessary to show my improvements. It is taken as on line xx of Fig. 2. Fig. 2 is an 55 end elevation of Fig. 1, the cap 17 being removed. Fig. 3 is an elevation of Fig. 1. Fig. 4 is an elevation showing the inside of the cap 17. It also shows the race 7 in position. The pawls 18 are omitted from Fig. 1 for the 60 sake of clearness.

Like numerals indicate corresponding parts.

The stationary parts of my spring-roller comprise the central spindle 1, preferably of 65 wood. At one end is a central projecting stud (not shown) as usually provided to support that end of said roller, and at the other end the spindle is continued in the form of a stud 2 of lessened diameter. This stud 2 has 70 a spike 3, which enters the spindle 1, a hole 4 in said spike being provided, and through which a pin or nail is driven to keep stud 2 in place. A metal thimble 5 is driven over the end of spindle 1 to prevent splitting. The 75 outer end of stud 2 carries a flattened projection 6, by means of which this end of the spindle is held in the usual bracket. The track or 80 race 7 is formed or cast in one piece with stud 2 and has notches 8. A portion of the spiral spring 9 is shown in Fig. 1, and its left-hand end is secured to the spindle 1 in known manner.

The revolvable parts of my spring-roller comprise the outer roller 10, preferably of wood. 85 Its left-hand end is journaled on the spindle 1 in known manner, while the right-hand end carries a casting or stamping 11, having two opposite arms 12, which are countersunk in the end of roller 10. One of the arms 12 is 90 channelled on its exposed surface, as at 13, and this channel receives the bent-over top end 14 of a pin or brad 15, which is driven into the end of roller 10, and whereby casting 11 is held in place. The other arm 12 is bored 95 through, as at 16, and the end of spring 9 is affixed to the roller 10 by being passed therethrough and bent or twisted to prevent slipping away. (See 9^a in Fig. 1.) A metal cap 17 incloses the race 7 and acts as a check to 100 prevent lateral movement of the parts. It also carries the pawls, whose action has already been mentioned. A great advantage of this construction lies in the fact that the

pawls and adjacent parts are covered, and thus protected from dust and fumes, which tend to clog or corrode them. The position of the pawls 18 is clearly shown in Fig. 4.

5 An undercut groove 19 is provided in the roller 10, and this serves as a ready means for attaching the blind thereto, which is done by having a hem made along its upper extreme edge and a slight rod or cane inserted therein. The edge thus thickened is slid longitudinally into the groove 19 and a true hang of the blind assured.

For the sake of clearly illustrating my invention the notches 8 are shown in Figs. 1 and 15 2 as occupying a horizontal line. They do in practice rest vertically, as shown in Fig. 4.

What I do claim as my invention, and desire to secure by Letters Patent, is—

In a spring-roller for blinds the combination of a fixed spindle, a roller free to revolve thereon, means for securing their relative positions, a spring to cause relative rotation, a casting 11 having hole 16 to which one end of the spring is secured, and a brad 15, with turned-over end 14 which lies in a channel 13 25 in said casting, whereby said casting is held in place in the roller 10, substantially as described.

WILLIAM SWARBRICK.
